GRINDING MACHINE

Andrew B. Utterback, Kenosha, Wis.

Application November 1, 1937, Serial No. 172,077

9 Claims. (Cl. 51—48)

This invention relates to improvements in grinding machines, particularly machines adapted for use in sharpening the rotary knives of lawn mowers.

5 One object of the invention is to provide a machine having a sharpening device, preferably a power operated grinding wheel, which can be so adjusted as to effect the disposition of the wheel in proper position for grinding the 10 blades of a lawn mower properly as the wheel is moved laterally of the machine in a predetermined path in the direction of the rotary axis of the blades. Since the cutting edges of the 15 rotary blades of conventional lawn mowers are curved or somewhat spirally arranged in the cylindrical path or orbits of rotation thereof and the grinding wheel is movable in a lateral direction, provision is made for rotating a blade during the sharpening operation so that successive 20 portions of the edge of the blade will move into a predetermined position with respect to the grinding wheel during the lateral movement of the latter whereby the edge of the blade will be ground uniformly throughout its length.

25 Another object of the invention is to provide a machine which is so adjustable with respect to a supported article to be sharpened that the grinding wheel of the machine is movable in such direction as to assure the desired uniform results.

30 With the present improvements, it is not necessary to adjust a lawn mower, whether of the hand or power operated type, or other device to be sharpened by the machine, in a precise position for grinding but only in a convenient grinding position since the adjustability of the present machine facilitates the expeditious adjustment of the grinding wheel to the edge to be sharpened. Thus, in grinding the blades of a lawn mower, the 35 blades can be ground properly by the present machine whether the rotary axis of the blades be positioned for grinding in a truly horizontal position or arranged precisely in a plane at right angles to the longitudinal axis of the machine or whether the blades to be sharpened have been 40 worn or ground down on one end more than on the other.

Other objects and advantages of the present improvements will be apparent from a consideration of the following specification and accompanying drawings, wherein:

Fig. 1 is a top plan view of a grinding machine embodying the present improvements, parts of the machine being shown in section for the purpose of clarity;

Fig. 2 is an end elevation of the machine shown in Fig. 1;

Fig. 3 is a broken vertical section taken on line 3—3 of Fig. 1;

Fig. 4 is a broken horizontal sectional view taken on line 4—4 of Fig. 3;

Fig. 5 is a broken sectional side elevation taken on line 5—5 of Fig. 1 showing a diagrammatically represented lawn mower in grinding position in the machine;

Fig. 6 is an enlarged broken sectional view taken on line 6—6 of Fig. 3;

Fig. 7 is a sectional view taken on line 7—7 of Fig. 6;

Fig. 8 is a perspective view of a blade guide member shown in detached relation;

Fig. 9 is a broken vertical section through the forward portion of the machine illustrating an additional mode of using the same in grinding power lawn mowers, for example; and

Fig. 10 is a detached perspective view of a modified guide plate shown in Fig. 9.

In the drawings, the machine as illustrated is particularly adapted for grinding the blades of lawn mowers although, as will be seen, it may be used for sharpening or grinding other articles as well. The embodiment of the invention selected for the purpose of illustration comprises a pair of longitudinally arranged bed members indicated generally by the numeral 10, each in the 25 embodiment illustrated, comprising a lower angle bar 11 and an upper flat bar 12. The bed members 10, at the rear ends thereof, are suitably attached to members 13 and intermediate the ends to similar members 14. Between the pair of 30 members 13, 13 and 14, 14 which are recessed, extend transverse brace or stiffening bars or rods 15 and 16, respectively, which are retained in recesses of the respective members 13 and 14 by any suitable means such as set screws 17 which 35 permit of the ready assembly or disassembly of the machine.

Extending longitudinally of the bars 12 are rods or shafts 18 which are provided with cranks 19 at their rear ends and are threaded as shown 45 at 18a throughout a portion of their length. These rods 18 are journaled in ears 13a and 14a of the members 13 and 14, respectively, and in a forward end plate 20 carried by the respective bed members 10.

Mounted on the bars 12 at each side of the machine are two standards 21 and 22 and 23 and 24, the first mentioned pair being at the left hand side of Fig. 1 and the latter pair on the opposite side. These standards are of similar construc-

tion and, as shown in Fig. 3, each is provided with a slot 25 at its lower end for receiving one of the bars 12 which constitute guides for the standards. The standards 21 and 22 are attached together for movement longitudinally of the bed in unison, a bar 26 being shown as the attaching means. The pair of standards 23 and 24 are likewise attached together by a bar 27.

The standards are provided at their lower ends with transverse openings 28 and 29 between which is a horizontal shelf or bridge 30. The lower opening 29 bisects the lower bifurcated portion and forms four legs, two arranged for disposition on the outside of the bar 12 and two on the inside of the bar. The outer legs are each designated by the numeral 31 and the inner legs by the numeral 32. As shown in Fig. 4, one of each of the legs 32 of the standards 22 and 24 is provided with a threaded horizontal passage 33 therethrough while the other is provided with a slightly larger unthreaded passage 34. The corresponding legs of the rear standards 21 and 23 are provided with unthreaded openings corresponding to the openings 34 of the leg 32 shown in Fig. 4. The front and rear standards are similar in form but differ with respect to the threaded openings just referred to.

The threaded shafts 18 at each side of the machine extend through the above mentioned unthreaded openings of the rear standards 21 and 23 and through the openings 33 and 34 of the legs of the rear standards. It will therefore be seen that as the shaft 18 is rotated by means of the respective cranks 19, the standards mounted on the respective shafts will be moved forwardly or rearwardly of the machine in unison, that is, turning the shaft at one side of the machine will move the pair of standards on that side while turning the shaft on the opposite side enables the corresponding pair of standards to be adjusted longitudinally and in unison.

The four standards are likewise provided with vertical shafts 35 having crank arms 36 at their upper ends, said shafts being journaled in transverse portions of the respective standards, such as portions 35a and 35b. Mounted on the threaded shafts in vertical slots or openings 37 in the standards are track supporting members 38 each having a pair of legs 38a and 38b through threaded openings in which the respective threaded shaft 35 extends. By rotating a shaft 35 by means of its crank 36, a member 38 may be raised or lowered depending upon the direction of rotation of the shaft. The slots 37 of the standards are wider than the thickness of the legs 38a (see Fig. 6) and hence the members 38 can pivot a limited extent about the respective shafts 35 to enable the transverse tracks to assume oblique positions with respect to the machine upon proper relative adjustment of the shafts 18.

The members 38 extend inwardly of the machine sufficiently to form supporting shoulders 38c, upon which may be positioned the ends of cylindrical tracks 39 and 40, that is, the two standards 21 and 23 by means of the respective members 38 support track member 39 while the standards 22 and 24 similarly support the transverse track member 40. The ends of each of the track members as shown in Fig. 3 are slotted to enable the same to slide downwardly over the shoulders 38c, the slotted ends being provided with suitable slotted plugs 41 to prevent oscillation of the respective tracks on a horizontal axis. Rotation of the left hand shaft 18, for example, in one direction will cause the two standards 21

and 22 to be moved forwardly of the machine or downwardly as viewed in Fig. 1, the brackets or supporting members 38 pivoting about their respective shafts 35 to enable the track members 39 and 40 to assume a diagonal or oblique position with reference to the bed members. It will be seen that while the tracks 39 and 40 may be raised or lowered by the respective shafts 35 and moved forwardly or rearwardly by their shafts 18, they remain in parallel vertical planes due to the fact that each pair of standards is connected by one of the side bars 26 or 27 and thus remains a fixed distance apart longitudinally of the machine.

The standard shown in Fig. 3 is standard 21 of Fig. 1, that is, it is one of the rear standards. Each of these rear shafts 35 preferably has a chain sprocket 42 mounted thereon at its lower end within the respective horizontal passage 28. Rotation of the shaft 36 of either of such standards will not only raise or lower the track supporting member 38 but will rotate sprocket 42 for operating a chain 43 passing over both said sprockets whereby one rear elevating shaft 35 may be operated by turning the crank 36 of the other shaft.

In assembling the machine, the track supporting members 38 of the rear standards 21 and 23 are arranged in horizontal alignment so that the track 39 will be horizontal. Since rotation of either rear shaft 35 will effect operation of the other by means of the chain 43, the track 39 may be raised or lowered by the operation of either of the rear shafts 35. The forward vertical shafts 35 are independently operable for altering the inclination of the track 40 with respect to the horizontal.

The grinding mechanism preferably comprises a carriage indicated generally by the numeral 44 which, at its rear end, supports an electric motor 45, on the shaft of which is mounted a belt pulley 46 which, by means of belt 47, drives a pulley 48 of a grinding wheel 49 suitably journaled adjacent the forward end of the carriage 44. The rear end of the carriage preferably is provided with a pair of wheels or rollers 50 which travel transversely of the machine upon the rear track 39. The forward end of the carriage is provided with a detachable plate 51 shown in detail in Fig. 8 which carries a forwardly projecting stud or shaft 52 upon which is mounted a single wheel or roller 53 which travels transversely of the machine on the forward track 40. This arrangement provides a carriage structure which may be lifted upwardly from the tracks or as conveniently replaced thereon. The shaft 52 is of such length as to enable the wheel 53 to move sufficiently longitudinally of the shaft to enable it to remain in engagement with the track 40 when the tracks 39 and 40 are adjusted to different horizontal positions.

A lawn mower to be sharpened is placed beneath the machine, which preferably is supported at a suitable elevation by means of legs 54, the lawn mower mechanism being inverted so that the handle 55 thereof extends downwardly. This disposition of the lawn mower provides access to the reel structure 56 which carries the cutting blades or knives 57. The lawn mower is supported in the position shown in dotted lines in Fig. 1 and in full lines in Fig. 5 by any suitable means such, for example, as a pair of brackets 58 removably secured to parallel arms 59 slidably positioned on the transverse members 15 and 16. The brackets 58 are

provided with suitably shaped recesses 58a, 58b and 58c for accommodating lawn mowers of different styles and sizes. In utilizing the supporting brackets 58 for holding a lawn mower in grinding position, the usual transverse guard rod 60 which extends transversely of the lawn mower forwardly of the blades may be made use of. In Fig. 5, the rod 60 is shown located in position in recesses 58a of the member 58.

When a lawn mower has been so positioned, the operator, by turning the shafts 18 by means of their cranks 19, advances the standards forwardly or rearwardly as may be necessary in bringing the grinding wheel 49 into approximate position over the blade to be sharpened.

By rotating the vertical shafts of either of the rear standards 21 and 23, the rear track member 39 may be raised or lowered but retained, however, in a horizontal position. Similarly, by operating the threaded shafts of the forward standards 22 and 24, the forward track member 40 may be raised or lowered more at one end than at the other, if desired, for effecting the proper disposition of the track for guiding the grinding wheel in the desired path of operation transversely of the machine.

The carriage end plate 51 is provided with an adjustable threaded stud 61 which, as shown in Fig. 5, is arranged to abut a surface of a blade 57 to be ground. The blades of lawn mowers are generally so shaped that the cutting edge thereof is helically disposed in the cylindrical surface of its orbit. When a mower has been placed in position on a machine initially, the tracks 39 and 40 are adjusted longitudinally of the machine and vertically to effect the disposition of the grinder wheel over one end of the blade to be ground when such end is in substantially the vertical position. As the carriage is moved transversely upon the tracks, the stud 61, when properly adjusted, will effect rotation of the blade reel so as to bring successive portions of the edge of the blade to be ground uniformly into grinding position. Should it be found, after making the initial setting of the machine to the grinding wheel, that the cutting edge of a blade does not remain in registration with a mark, such as the pencil mark 62 formed on the side of the grinding wheel, as the wheel is moved transversely of the machine, one or the other of the shafts 18 is adjusted to align the path of movement of the mark 62 with the cutting edge of the blade so that the blade will be ground uniformly throughout its length if desired, it being understood that the forward track 40 is adjusted vertically so as to assure such result. Should a blade have been sharpened at one end more than at the other, the grinder can be caused to move into proper grinding contact with such edge by vertical adjustment of the ends of the forward track 40 so that as the carriage is reciprocated, it grinds uniformly along the length of the blade. Should a mower having such improperly ground or unevenly worn edges be placed in the machine for the purpose of truing up the edges so that they are of uniform distance throughout from the rotary axis of the reel, the forward track member is adjusted so that at each end of the grinding operation on each blade, the cutting surface of the grinding wheel will be a predetermined distance from the rotary axis of the reel.

Lawn mowers of different sizes and makes may be supported in recesses 58a, 58b or 58c as found most convenient. Mowers of certain un-

usual makes may require the removal of the brackets 58 as by releasing the wing nuts 58d, for example, and placing the brackets farther rearwardly of the machine and attaching them at the openings 58e, for example.

In sharpening lawn mowers of the power type, it has been found necessary or desirable to support the same by means other than the brackets 58. In Fig. 9, for example, 64 indicates generally a power type lawn mower which may be supported by any suitable means, such as a jack or by chains (not shown) or upon a pedestal or stationary support shown diagrammatically at 65. In sharpening such a mower, the plate 51 shown in Figs. 1 to 5 and Fig. 8 is removed and a plate of the type disclosed in Fig. 10 is substituted. This plate indicated generally by the numeral 66 is provided with a threaded boss 67 which carries an adjustable threaded stud 68 which engages a surface of a blade as above described for turning the blade as the carriage is moved laterally for effecting the disposition of successive portions of the blade in proper grinding relation with respect to the grinding wheel. The plate also is provided with a second threaded stud 69 which contacts and slides along the bed or shear blade 70 of the machine which is shown in inverted position. The carriage 44, instead of traveling on the two tracks 39 and 40 is arranged with the rear portion 36 thereof over the forward track 40. The forward end of the carriage is guided by the contact of the stud 61 with the bed plate 70 of the machine. The disposition of the carriage for grinding a power or other lawn mower which cannot be supported by the brackets 58 is indicated in Fig. 1 also in dotted lines. By adjusting the stud 68, the forward end of the carriage can be raised or lowered, which movement can also be effected by the vertical adjustment of 40 the track 40 by the operation of its vertical shafts 39 as above described. For sharpening the bed or shear blades of a lawn mower, that is, such as the blade 70 of the mower shown in Fig. 9, it may be positioned upon the brackets 45 58 and the machine adjusted so as to effect the proper grinding relation of the wheel 49 with the edge of the blade to be ground, the blade being preferably attached to the brackets 58 by any suitable means such as clamps or held 50 in position manually during the grinding operation.

The construction of the grinding machine above described is such that the grinding wheel is adjusted into proper grinding relation with an edge or article to be sharpened while the latter is supported in a convenient position arranged generally transversely of the machine although, due to the latitude of adjustment of the grinding wheel, the precise adjustment of 60 the edge to be ground either with respect to a horizontal plane or with reference to its angle to the longitudinal axis of the machine is not required. In other words, the edge to be ground may be disposed at an angle to the horizontal 65 and also somewhat diagonally of the bed of the machine since the adjustments described enable the grinding wheel to be moved laterally of the machine to effect a proper grinding of such edge throughout its length. In actual use, it has been 70 found that where a mower is supported as described by brackets 58, adjustment of the forward track 40 from parallel position with respect to the rod 60 is necessary, due probably to wear of bearings or other parts during use.

When the grinding wheel has been adjusted to the proper position, the current to the motor is turned on as by a convenient switch 12 shown in Fig. 1 and the carriage moved by hand transversely of the machine from one end of the blade to the other. If more than one passage of the grinding wheel across the length of the blade is required, the operator may turn one of the cranks 36 of the rear standards 21 and 23 in a direction to lower the track 39 leaving the forward track in its original position. Since the distance from the center of the grinding wheel to the track 39 is considerably greater than the distance from the center of the grinding wheel to the track 40, the lowering of the track 39 can be so effected as to so lower the grinding wheel that on the second passage of the same along the edge, only a minute cut of the blade edge will be made. Due to the fine adjustment possible by this arrangement, the blades can be ground to within extremely close dimensions. In the present embodiment of the invention, the ratio of the distance from the center of the grinding wheel to the rear track to the distance from the center of the grinding wheel to the forward track is approximately four to one.

While I have shown and described certain embodiments of my improvements for the purpose of illustration, it will be apparent that various changes in construction may be made therein without departing from the spirit of the invention.

I claim:

1. A grinding machine comprising a pair of parallel bed members, connected front and rear standards on each bed member movable as a unit longitudinally of the respective bed member, a pair of transverse tracks one carried articulately by the front pair of said standards and the other track by said rear pair of standards, means for adjusting the standards of each bed member longitudinally of the respective bed members for advancing or retracting the track members longitudinally of said bed, said adjusting means being independently operable for disposing the tracks in vertical planes parallel with a vertical plane through a member to be ground and disposed generally transversely with respect to said bed members, means carried by said standards for varying the elevation of said tracks, and a carriage mounted on and movable longitudinally of said tracks and comprising a grinding wheel for grinding the member to be ground.

2. Sharpening apparatus of the class described comprising a pair of spaced bed members, a pair of standards on each of said members movable along the same as a unit, transverse track members supported by corresponding standards of said pairs, grinding means on said members comprising a carriage having a grinding member movable longitudinally of said track members, and mechanism for adjusting said grinding member into grinding relation with a member to be sharpened comprising means for adjusting said track members longitudinally of said bed and vertically within parallel vertical planes.

3. Sharpening apparatus comprising a pair of parallel bed members, a pair of standards carried by each bed member, each pair of standards being movable as a unit longitudinally of the respective bed members, transverse front and rear track members articulately attached to the front and rear standards of said pairs of standards, a carriage comprising a grinding wheel movable longitudinally of said track members, and

means for adjusting said standards longitudinally of said bed and vertically of said standards into grinding relation with a device to be sharpened disposed generally transversely with reference to said bed members.

4. A grinding machine comprising a bed, a pair of transverse tracks disposed above the same in parallel vertical planes, a carriage movable on said tracks in the direction of the length thereof and comprising a grinding wheel reciprocal by 10 said carriage in grinding relation with a blade to be ground, vertically adjustable supports for the ends of said tracks for varying the elevation thereof, and means for independently advancing or retracting said track supports and tracks longitudinally of the machine for varying the angular disposition of the tracks with respect to the bed.

5. A grinding machine comprising a carriage having a grinding wheel thereon, tracks supporting said carriage for reciprocation longitudinally thereof, supporting means for the ends of said tracks, means for effecting the adjustment of said supporting means vertically for altering the elevation of said tracks and the carriage thereon, and means for effecting the longitudinal adjustment of said track supporting members for varying the angular disposition of said tracks with respect to the longitudinal axis of the machine for effecting the alignment of the path of reciprocation of the grinding wheel with the edge of a 30 device to be ground.

6. A grinding machine comprising a pair of parallel bed members, front and rear standards on each of said bed members, articulate track supports carried by said standards, a pair of track members one carried by the track supports of said front standards and the other by the track supports of said rear standards, a carriage reciprocal on said tracks longitudinally thereof, a grinding wheel on said carriage, means for independently adjusting each pair of said standards longitudinally of the bed members for effecting a predetermined angular disposition of said tracks with respect to said bed and means for independently adjusting said front supports vertically 45 whereby said front track can be disposed at an angle to the horizontal for guiding said wheel in grinding relation with respect to an edge to be ground.

7. A grinding machine comprising a supporting bed, a pair of track members disposed in parallel vertical planes, supporting means for said track members carried by said bed, means for adjusting in unison corresponding ends of each track member longitudinally of said bed, means for independently adjusting said tracks vertically, a reciprocal carriage on said track members, a grinding device on said carriage, and track engaging wheels on said carriage shiftable relatively axially for accommodating the same to variations in the 60 longitudinal spacing of said tracks during adjustment of the same.

8. A grinding machine comprising adjustable front and rear track supports, one of each being arranged at opposite sides of the machine, front and rear tracks articulately supported at each end by the corresponding supports, grinding means comprising a wheeled carriage reciprocal on said tracks and comprising a motor operated grinding wheel located intermediate the ends of 70 said carriage, and mechanism for adjusting said wheel into grinding relation with respect to an edge to be ground during reciprocating movement of the carriage comprising means for simultaneously adjusting said rear track supports ver- 75

tically, means for independently adjusting said front track supports vertically, and means for independently adjusting the track supports at either side of the machine longitudinally thereof.

5 9. A grinding machine comprising a bed, a pair of tracks, a carriage reciprocable longitudinally of said tracks, a grinding wheel carried by said carriage, a pair of front and a pair of rear adjustable supports for articulately supporting the ends of said tracks, means for relatively adjusting the front pair of supports vertically, means

for simultaneously adjusting said rear pair of supports vertically and means for simultaneously adjusting one front and one rear support longitudinally with respect to said bed and independently of the other supports for effecting the disposition of said tracks for guiding the reciprocable movement of said grinding wheel in pre-determined relation with respect to an edge to be ground. 5

ANDREW B. UTTERBACK 10
